(57) CLAIM

The ornamental design for a pedal combination for vehicle, as shown and described.

DESCRIPTION

FIG. 1 is a front view of pedal combination for vehicle showing our new design; and,

FIG. 2 is a front, perspective view thereof.

The features shown in uniform broken lines are portions of the pedal combination for vehicle that form no part of the claimed design.

1 Claim, 2 Drawing Sheets
